GARMENT

Edward Hauser, Woodhaven, N. Y.

Application September 21, 1935, Serial No. 41,536

1 Claim. (Cl. 2-212)

This invention relates to improvements in garments and more particularly to men's and women's bathing trunks.

The brevity and tight fit of the present style bathing trunks when worn, exposes various lines of the wearer's anatomy which to some wearers may be embarrassing. It is therefore the primary object of this invention to provide a stylish garment of the above kind which combines an outer undivided skirt with an under crotch covering garment which when worn, conceals the buttocks and crotch of the wearer, while affording seat snugness and body freedom.

Another feature of the invention resides in a bathing or play suit having an outer skirt part and an under crotch covering part joined together by pairs of spaced front and back seams which are disposed well on the outer sides of the thighs and buttocks of a wearer when the garment is in use to prevent the under crotch covering part from revealing a pulling effect on the outer skirt part when the wearer is seated or stooping. During such action on the part of a wearer, the crotch line over the wearer's buttocks lengthens and unless the joining seams follow the flat outer surface of the thighs and buttocks, a pulling in effect will show on the outer skirt part.

Another feature of the invention resides in a bathing trunk having an outer skirt part and an under crotch covering part, portions of the skirt part combining with the crotch covering part to provide leg openings, thus preventing bulkiness, reducing the amount of material used in the making of the garment to a minimum, and accordingly lessening the cost of manufacture.

A further object of the invention is the provision of a combination garment of the above kind in which the crotch covering part and skirt part are joined together in such manner that the skirt part always conceals the crotch at the front and back of a wearer, and is prevented from sliding upward regardless of how active the body may be.

With these and other objects in view, the invention resides in the combination and arrangement of parts, the essential features of which will be hereinafter fully described in the specification, pointed out in the appended claim, and illustrated in the accompanying drawing, in which: Figure 1 is a perspective view of one embodiment of my combination garment constructed of knitted material showing the same in position upon a wearer, and looking at the rear thereof.

Figure 2 is a perspective view of the garment looking at the front thereof.

Figure 3 is a vertical central longitudinal sectional view.

Figure 4 is a horizontal sectional view.

Referring to the drawing by reference characters the numeral 10 designates the combination garment in its entirety and which is constructed of knitted material having sufficient give to facilitate the donning and removal of the same without the necessity of buttonable plackets.

The single garment broadly includes an outer 10 undivided skirt part A and an under crotch covering part B, coacting with the part A to form leg openings C-C adjacent the bottom of the skirt part. The top of the skirt part is shaped 15 to form a waist encircling band D which has loops 15 E spaced therearound for the passage of a belt F as shown in Figure 1.

The outer skirt part A includes four sections, 20 namely a front section 11, two identical side sections 12-12, and a rear or back section 13. The front section 11 has its opposite side edges joined to adjacent front edges of the side sections 12 by stitching 14, and these joined edges are disposed at the front of the garment and form seams 15-15. The meeting edges of these joined sections are cut and stitched so that the seams 15-15 converge upwardly from the bottom edge 25 of the skirt part to the waist portion D thereof. The side edges of the rear section 13 are likewise cut to converge upwardly and are stitched to adjacent rear edges of the side sections 12-12 to form upwardly converging back seams 16-16. The upwardly converging front seams 15-15 30 overlie the outer sides of the respective thighs of a wearer, while the upwardly converging back seams 16-16 overlie the outer sides of the respective buttocks.

Secured to the inside of the front section 11 35 is a front crotch covering part 17 which includes a pair of identical sections 18-18 having inner straight edges which are stitched together to provide a downwardly and rearwardly extending seam 19. The outer side edges of the sections 18-18 are secured to the outer skirt part by the stitching 14. The lower outer edges of the sections 18-18 are curved and shaped to fit the curvature of the thigh of a wearer.

Underlying the back section 13 is a rear crotch 40 covering part 20 which includes a pair of identical sections 21-21 similar to the sections 18-18 of the front crotch covering part 17. The straight meeting edges of the sections 18-18 are stitched to provide a downwardly and forwardly extending seam 22. The sections 18-18 and 21-21 45 meet and are secured by stitching to provide a 50

55

cross seam 23. All of the seam stitching is performed while the parts are inside out, after which the stitched garment is reversed to hide the stitching from the outside, thus making only the 5 seams visible.

To flatten the merging seams that overlie each thigh, the front center skirt section 11 is made narrower in width than the combined width of the underlying crotch covering sections 18-18. 10 The skirt front will pull the seams flat with its strong or side pull, over the lesser side stretched material of the under sections.

The crotch covering sections 17 and 20 extend from the inturned waist hem 24 to a point just 15 short of the bottom hem 25 thereof, the bottom edges of the sections 18-18 and 21-21 being hemmed as at 26 as best seen in Figure 2 of the drawing.

From the foregoing description, it will be seen 20 that the side sections 12-12 of the skirt part A coact with the crotch covering sections 18-18 and 21-21 to provide the under crotch covering part B, the crotch covering part being normally concealed from view by the lower part of the un- 25 divided skirt part A. When the garment is in position upon a wearer, the same fits snugly about the legs and crotch while the skirt portion will always be held down in crotch concealing position. This construction eliminates the uncom- 30 fortable riding up of the skirt part relative to the crotch covering part.

In Figure 4 of the drawing, I have illustrated a line X-X drawn transversely through one of the leg openings C to more clearly show the rela-

tive position of the front and rear seams 15 and 16 respectively, with respect to the thigh of a wearer. Assuming that the line X-X indicates substantially the fore and aft center of the wearer's thigh, the seams 15 and 16 are disposed on 5 a plane outwardly thereof, so as to overlie the outer curves of the wearer's thighs and buttocks.

Having thus described the invention, what I claim as new and desire to secure by Letters Patent of the United States, is:— 10

A bathing garment adapted to extend from the waist line to a point below the crotch and comprising a tight fitting outer skirt part composed of opposed relatively narrow side pieces and relatively wide intermediate front and back pieces 15 and an inner member having front and back body covering parts extending from adjacent the waist line and including a crotch, said front and back parts of the inner member being continuous between their side edges and coextensive in width 20 with the front and back intermediate pieces of the skirt, the side edges of the front and back pieces of the skirt being secured to the adjacent side edges of the inner member and to the adjacent side edges of the side pieces of the skirt 25 by straight vertical seams which overlie the thighs and buttocks of the wearer and which seams extend substantially throughout the length of the garment, the lower edges of said crotch and the lower edges of said side pieces cooperating to tightly encircle the legs of the wearer 30 to prevent upward movement of the skirt.

EDWARD HAUSER.
